UNITED STATES PATENT OFFICE

ALFRED LIEBERGELD, OF LAUFAMHOLZ, NEAR NUEREMBERG, GERMANY, ASSIGNOR TO
FRITZ SINGER, OF NUEREMBERG, GERMANY

EXTRUSION PRESS

Application filed September 29, 1930, Serial No. 485,020, and in Germany July 12, 1928.

My invention pertains to extrusion presses, and more particularly to the means for imparting movement to the tool or tools employed therein.

5 In the extrusion of metals, for instance to produce tubes, rods and the like, it is important that the operation be conducted at the highest speed which is possible consistently with the obtaining of a satisfactory product. This is in order that cooling-off of the billet (which would diminish its plasticity) may be minimized and an excessive heating of the tools, by long contact with the hot billet, be avoided. It is further desirable that the flow of the metal be initiated at a certain minimum speed; since otherwise there would be danger of the part first extruded becoming cooled sufficiently to freeze fast in the aperture of the extruding die. 15 After the flowing of the metal has been initiated, there is nothing to prevent the extruding of the main part of the billet from being performed at a speed which is substantially constant and which is as high as is possible consistently with the characteristics of the metal being extruded and other well understood extrusion conditions. The extruding of the last part of the billet should, however, be performed at a lessened speed 20 and under an increased pressure in order to meet conditions arising from the cooling and diminished plasticity of the billet at that stage. 25 Following out of the speed and pressure formula stated above will give an extrusion speed higher than the ordinary and excellent results; however, it has been difficult of accomplishment with extrusion presses as heretofore constructed. In hydraulic presses the maximum force exerted results unalterably from the water pressure, diameter of plunger and efficiency of the press. In such a press the speed is not predetermined, but is governed by the reciprocal action of the maximum pressure applied by the press, the throttling action at any given movement of the controlling valve, and the resistance of the billet at that moment against deformation. In hydraulic presses the possibilities 30 of influencing the proportions of speed and pressure by throttling or shutting and re-opening the controlling valve are only very limited. Likewise, in the case of mechanically driven presses as heretofore ordinarily used, such as the rack and pinion and crank presses, the laws governing the motions of such presses closely control the speed and pressure effects obtainable. In the case of crank presses, for example, it must be presupposed that the motor power and fly-wheel masses will be sufficient, and from these the speed unalterably results, whilst the pressure exerted is determined by the resistance of the billet to deformation. It is true that in 35 crank presses the speed of the extruding tool gradually increases from zero to a maximum and then decreases again gradually to zero. However, in designing such a press with a view to shortening the extrusion time as much as possible, there is encountered a maximum speed, towards the center of the stroke, which is sometimes disadvantageous, coupled, at the end of the stroke, with a retardation which is excessive and beyond anything that is required for the extruding of the billet 40 remainder. Presses of the kinds referred to, therefore, have not been capable to a sufficient extent of employing at the various extruding stages those speeds and pressures which are best calculated to shorten the total time of 45 extrusion and at the same time give a satisfactory product. Moreover, with such presses difficulty has been experienced in slowing up or stopping the extruding operation while in progress, as is often desirable, 50 for example, in extruding wire in order to enable a workman to insert the end of a new length of wire into a reel. 55 With the above in view, the principal object of my invention is to provide an extrusion press in which, by means simple in character and capable of withstanding the heavy forces to which they are subjected, the speeds and pressure forces at which the extrusion tool or tools operate can be fully accommodated, at each phase of the stroke, to the requirements of the extrusion process. It is a further object of my invention to provide 60 such an extrusion press in which, by simple means, extrusion can be slowed down tempo- 65

rarily or stopped at any stage desired. And other objects of my invention, and advantages obtained thereby, will appear from the following specification.

6 By way of example, I have shown in the accompanying drawings, and described in the following specification an extrusion press embodying one form of means according to 10 my invention for imparting movement to the extrusion tools. It is to be understood, however, that my invention may be embodied otherwise, and that changes may be made in the particular construction described and shown without exceeding the scope thereof 15 as defined in the appended claims.

In the drawings:

Fig. 1 is a side elevation, partly in section, of an extrusion press constructed in accordance with my invention, shown in its initial 20 position, with a billet in place in the container, ready for extrusion;

Fig. 2 is a front view of the press, likewise partly in section;

Fig. 3 is a rear view of the press;

25 Figs. 4-7 are views similar to Fig. 1 showing the parts in the positions which they assume, when the plunger contacts the billet just prior to the piercing operation, when the mandrel has pierced the billet prior to the 30 extruding operation, when the extruding operation has just been completed and it remains necessary to sever the residue, and when the residue has been severed, respectively;

35 Fig. 8 is a plan of the press, partly in section;

Fig. 9 is a fragmentary vertical section through the plunger head and billet container showing a modified form of shearing-40 off means employed when solid rods or the like are to be extruded.

Referring now to Figs. 1 to 8 the extrusion tools, and means for imparting motion to the same, shown therein for purposes of illustration are adapted for producing a tube by first piercing a billet, then extruding the latter and then cutting off the residue remaining in the billet container after the extrusion has been completed. As shown in 45 such figures, the press includes a frame 1 carrying a fixed table 2 upon which is mounted the billet container 3, in the lower end of which is secured the female die 4. Mounted to slide vertically in suitable ways with 50 which the frame 1 is provided is a punch carrier 5 to the lower part of which is secured the punch 6, the latter being made hollow for the passage therethrough of a mandrel carrier 7 and mandrel 8. In the lower part of the 55 punch is slidably mounted a centrally disposed shearing member 9 having a shoulder 10 adapted to engage the interior of the punch and thereby retain the shearing member in place in the latter. An abutment 60 member 11 is secured within the punch for

engagement by the shoulder 10 of the shearing member, the parts being preferably of such dimensions that when the shoulder 10 engages the abutment member 11 the outer end of the shearing member is flush with the end of the punch. The shearing member is made tubular to permit the passage therethrough of the mandrel 8 and is adapted to be engaged, at one stage in the cycle of the press, by a shoulder 12 formed at the junction 75 between the mandrel carrier 7 and the mandrel. When thus engaged by the shoulder 7 the shearing member 9 is forced downwardly with respect to the punch for the purpose of shearing-off the residue.

The punch carrier 5 and mandrel carrier 7 are independently actuated, the cycle being as follows: First, the punch carrier and mandrel carrier are moved downward until the punch 6 touches upon the billet 13 in the container (Fig. 4). Next, the mandrel carrier is forced downward with respect to the punch carrier to cause the mandrel 8 to pierce the billet, during which time the punch carrier may be given a slight upward or retiring movement to accommodate the upward flow of metal resulting from the piercing of the billet (Fig. 5). Next, the punch carrier is forced downward until it has extruded the billet through the female die 4 and around the mandrel 8 to produce the tube 14 (Fig. 6), during which time the mandrel carrier 7 may remain stationary, if desired, or may have some movement in either direction. Next, the mandrel carrier is given a further downward movement to cause its shoulder 12 to engage the shoulder 10 of the shearing member 9 and cause such shearing member to move downward beyond the end of the punch 6 and enter the hole in the female die 4, thereby shearing off the tube 14 from the residue 15 remaining in the billet container (Fig. 7). Thereafter the parts are returned to their initial position (Fig. 1) ready for the insertion of another billet into the container 3.

For actuating the punch carrier 5 a pair of punch-actuating toggles is employed, one at each side of the press. They are similar, and a description of one pair, therefore, will suffice. Each pair of toggles comprises a link 16 pivoted to the upper part of the press and a link 17 pivoted to the punch carrier 5, the links 16 and 17 being pivoted together in the usual manner. Each toggle link 16 is formed with a rearward extension 18 in which is mounted a cam roller 19 adapted to bear upon a reciprocating cam 20, one of which is provided for each pair of punch-actuating toggles.

The cams 20 are connected together through the intermediary of spacers 21 and a central cam 22 (further reference to which will be made below) to constitute a cam assembly which is mounted for vertical slid-

ing movement in a pair of ways 23, one of which is disposed on each side of the press (Figs. 1 and 8). The rear edges of the cams 20 are disposed vertically and are formed to constitute racks 24 meshing with pinions 25 carried by a pinion shaft 26, disposed at the rear of the press. Rotary movement, first in one direction and then in the other, is imparted to the pinion shaft in any one of a number of manners well understood in the art. Such movement may be uniform or non-uniform in the extruding direction, since if non-uniform any variations can be accommodated by the contours of the cams. The pinion shaft, moreover, by well understood means, may, if desired, be made to rotate more rapidly in the return direction than in the extruding direction.

In order to maintain the rollers 19 firmly in engagement with the cams 20, and to cause such rollers to rise, in engagement with the cams, during the upward movement of the latter, each of the cams has pivoted thereto a pressure cylinder 27, the piston 28 of which is connected with the extension 18 of the link 16 of the associated toggle. Upward pressure is applied to the pistons 28 by water, air or the like.

The cams 20, which are identical, straighten on the toggles 16, 17, thereby to perform the extruding operation during their downward movement. Each cam is formed with a substantially horizontal surface *a*, which is the first operating surface to engage the associated cam roller 19 during the downward movement of the cam. When the cam surface *a* bears upon the cam roller, the latter is forced downward, and, owing to the toggle linkage, must, of course, move forwardly, a straightening movement thereby being imparted to the toggle and the punch carrier 5 being moved downward. Above the cam surface *a* each cam is formed with a surface *b* which inclines slightly rearwardly, so that when this surface is in action the associated toggle will collapse somewhat and the punch carrier 5 rise a little. Above the cam surface *b*, each cam is formed with a surface *c* which is inclined towards the horizontal, thereby causing a straightening movement of the associated toggle, and is of such shape that the punch carrier 5 is forced downward at a speed which is substantially constant and is as high as possible taking into consideration the metal being extruded, etc. Above the surface *c* each cam is formed with a surface *d* which inclines more toward the vertical than the surface *c*, with the effect that the speed of downward movement of the punch carrier 5 is lessened, and the pressure exerted by the punch carrier is correspondingly increased. This surface *d* is timed to come into action at the extrusion of the last part of the billet. Above the surface *d* each cam is formed with a substantially vertical surface

e, so that while this surface is in action the punch carrier 5 remains stationary.

The means for operating the mandrel carrier 7 is very similar to that for operating the punch carrier 6, and includes a mandrel actuating toggle disposed centrally of the press. Such toggle comprises a link 29 pivoted to the upper part of the press frame 1 and a link 30 pivoted to the upper end of the mandrel carrier 7, the links being pivotally connected with each other in the usual manner. The link 29 is formed with a rearward extension 31 carrying a cam roller 32 which engages the cam 22 above referred to. A pressure cylinder 33 is pivoted to the cam 22, and the plunger 34 thereof is connected with the extension 31, so as to keep the cam roller 32 in engagement with the cam 22 in the same manner as the cam rollers 19 are kept in engagement with the cams 20.

The cam 22, which, of course, moves coincidentally with the cams 20, is formed with a substantially horizontal surface *a'* which is in action at the same time as the surfaces *a* of the cams 20, having the effect of moving the mandrel carrier 7 downward. Above the surface *a'*, the cam 22 is formed with an inclined surface *b'*, which is in action at the same time as the surfaces *b* of the cams 20, causing the mandrel carrier 7 to continue to move downward while the punch carrier 5 is moving slightly upward. Above the surface *b'*, the cam 22 is formed with a surface *c'* which is in action at the same time as the surfaces *c* and *d* of the cams 20 and which, in the construction shown, causes the mandrel 8 to move downward while the punch carrier 5 is moving likewise. Above the surface *c'*, the cam 22 is formed with a surface *e'* which is inclined towards the horizontal, thereby causing the punch carrier 7 to move downward, and is in action at the same time as the surfaces *e* of the cams 20, which maintain the punch carrier stationary.

It will be understood that the actual contours of the various surfaces of the cams will vary in accordance with the metal being extruded and the article produced. For example, the contours of the cams employed when wire is to be extruded will be different from those of the cams used in extruding tubes.

The operation of the press is as follows:

With the parts in the position shown in Fig. 1, the heated metal billet 13 is inserted in the container 3 and the press is started, whereby the cams 20 and 22 are caused to move downward in the ways 23 by the rack and pinion movement 24, 25. The surfaces *a* and *a'* of the cams 20 and 22 being substantially horizontal and coming into action simultaneously, the rollers 19 and 32 are simultaneously moved downward and towards the press frame. The result is that the punch carrier 5 and mandrel carrier 7

move downward together and the toggles 16, 17 and 29, 30 are partly straightened, the punch carrier 5 and mandrel carrier 7 moving downward together until the punch 6 touches upon the billet 13 (Fig. 4). Thereupon, during the further downward movement of the cams, the surface *b'* of the cam 22 comes into action, causing the mandrel carrier 7 to continue its downward movement although, due to the vertical surfaces *e* of the cams 20 are in action, allowing the toggles 16, 17 to collapse somewhat and the punch carrier to be raised a little under the pressure of the piston 28. Thus the mandrel 8 continues its downward movement, piercing the billet, while the punch recedes a little, to provide for the upward flow of the metal resulting from such piercing (Fig. 5). During the further downward movement of the cams, the surfaces *c* and *d* of the cams 20 successively come into action, causing the punch carrier first to be forced downward at a relatively high speed and then, towards the end of its stroke, at a lower speed. At the same time, in the construction shown, the surface *c'* of the cam 22 is in action and is causing the mandrel 8 to descend with the punch, thereby bringing the parts to the position shown in Fig. 6, where the billet is entirely extruded, leaving only the residue 15 in the container. As the cams move downward further, the surface *e'* of the cam 22 comes into action, causing the mandrel carrier 7 to continue its downward movement, although, due to the vertical surfaces *e* of the cams 20, the punch carrier 5 remains stationary. Such further downward movement of the mandrel carrier brings its shoulder 12 into engagement with the shoulder 10 of the shearing member 9, whereby such shearing member is forced downward with respect to the punch 6 so as to enter the aperture of the female die 4, thereby shearing-off the tube 14 from the residue and ejecting the tube from the die. This completes the downward movement of the cams. Upon their upward movement, of course, the parts return to the original position shown in Fig. 1.

It will be seen that, by the above cam construction, the speeds and pressures at which the extruding tool or tools operate at any stage in the cycle, can be determined in complete accordance with what may be found to be desired. Further, by properly shaping the cams, the extrusion step may be slowed down or stopped at any point in order to meet such practical conditions as may present themselves, as for instance where the end of a new length of wire is to be inserted in a reel, etc.

In the extrusion of rods and other solid articles, the piercing step will, of course, be omitted. In that event a plunger 7' (Fig. 9) may be employed in place of the mandrel

carrier 7, and its end made to engage against a solid shearing member 9' used in place of the hollow shearing member 9. The cam contours will, of course, be modified accordingly.

I claim:

1. An extrusion press comprising a pair of members mounted for coaxial reciprocating movement, a toggle device for each of said members to effect movement thereof, and a cam for each of said toggle devices to actuate the same.

2. An extrusion press comprising a reciprocating member, a toggle device for actuating the same, a reciprocating cam for operating said toggle device, and a pressure cylinder associated with said toggle device to maintain the same in operative relation with said cam.

3. An extrusion press comprising a pair of members mounted for coaxial reciprocating movement, a toggle device for each of said members to effect movement thereof, a reciprocating cam for each of said toggle devices to actuate the same, and a pressure device associated with each of said toggle devices to maintain the same in operative relation with their respective cams.

4. An extrusion press comprising a reciprocating extruding member, a toggle device for actuating the same, and a cam for operating said toggle device, said cam being shaped to impart to said member an initial extruding movement, then a further extruding movement at a higher and substantially constant speed, and then a final extruding movement at lower speed.

5. An extrusion press comprising an extruding member mounted for reciprocating movement, a tool mounted coaxially with said extruding member, a toggle device for actuating said tool, a pair of toggle devices, one on each side of said first-named toggle device, for actuating said member, a cam for actuating said first-named toggle device, and cams for actuating said pair of toggle devices.

6. An extrusion press comprising an extruding member mounted for reciprocating movement, a tool mounted coaxially with said extruding member, a toggle device for actuating said tool, a pair of toggle devices, one on each side of said first-named toggle device, for actuating said member, a reciprocating cam for actuating said first-named toggle device, reciprocating cams for actuating said pair of toggle devices, and means for reciprocating said cam and cams together.

7. An extrusion press, comprising a reciprocating member, a toggle device for operating the same, a reciprocating cam adapted to be moved in a direction parallel to the direction of reciprocation of said member, means for transmitting the movement of said cam

- to said toggle device, a second member guided within said first-named member and adapted to reciprocate in the same axis as said first-named member, a second toggle device for operating said second-named reciprocating member, a second cam adapted to be moved in a direction parallel to the direction of reciprocation of said second-named member, and means for transmitting the movement of said second-named cam to said second-named reciprocating member. 8. An extrusion press for extruding tubes comprising a hollow extruding punch, a shearing off member movably mounted in said punch, a mandrel mounted for reciprocating movement in said punch, said mandrel having a shoulder associated therewith for engagement with said shearing off member, a toggle device for actuating said punch to perform the extruding operation, a second toggle device for actuating said mandrel to pierce the billet and subsequently to cause said shoulder to engage said shearing off member to actuate the latter, and reciprocating cams for operating said toggle devices. 9. An extrusion press as set forth in claim 8 comprising a reciprocating cam for actuating the toggle device for the punch, said cam being shaped to move the punch at high speed up to the time of reaching the billet, then to permit a backward movement of the punch during piercing of the billet, then to move the punch downward to initiate flow of the metal in extruding the billet, then to move the punch downward at a higher speed to extrude the main portion of the billet, and then to move the punch downward at a lower speed to extrude the last portion of the billet. 10. An extrusion press as set forth in claim 8 comprising a reciprocating cam for actuating the toggle device for the punch, said cam being shaped to move the punch at high speed up to the time of reaching the billet, then to permit a backward movement of the punch during piercing of the billet, then to move the punch downward to initiate flow of the metal in extruding the billet, then to move the punch downward at a higher speed to extrude the main portion of the billet, and then to move the punch downward at a lower speed to extrude the last portion of the billet, and a reciprocating cam for the toggle device for the mandrel, said last-named cam being shaped to move the mandrel downward with the punch until the latter reaches the billet, to move the mandrel downward, to pierce the billet, during the backward movement of the punch and to move the mandrel downward after the extruding operation to actuate the shearing off member. 11. An extrusion press comprising a hollow extruding punch, a shearing off member movably mounted in said punch, an element mounted for reciprocating movement in said punch and adapted for engagement with said shearing off member, a toggle device for actuating said punch to perform the extruding operation, a second toggle device for actuating said element to cause it to engage and operate said shearing off member, and reciprocating cams for operating said toggle devices. In testimony whereof, I hereunto sign my name.
